UNITED STATES PATENT OFFICE.

AUGUST BUERMANN, OF NEWARK, NEW JERSEY.

DESIGN FOR SPURS.

SPECIFICATION forming part of Design No. 11,715, dated March 30, 1880.

Application filed August 27, 1879. Term of patent 7 years.

To all whom it may concern:

Be it known that I, AUGUST BUERMANN, a citizen of the United States, residing at Newark, in the county of Essex and State of New Jersey, have invented and produced a new and original Design for Spurs, of which the following is a specification, reference being had to the accompanying drawings, forming a part thereof.

10 In said drawings, Figure 1 is a side view of my newly-designed spur. Fig. 2 is a detached view of the rowel.

15 In my configuration the arms which hold the rowel are rounded at their outer extremities and formed with openings through them, the rowel also being provided with openings, so that when it is in position between the arms the open-work of the rowel is shown through the openings in the rowel-arms; and the leading feature of my design consists in forming 20 the spur so as to produce such general effect.

In the drawings referred to, A designates the rowel-arms, the same being rounded at their outer extremities and formed with the openings C.

The rowel (indicated by B) is made with openings f between the center G and the periphery H, which is the base of the spur-points K, so that the open-work of the rowel may show through the openings in the rowel-arms, thus 25 producing a novel and ornamental appearance in the spur.

I claim—

The design for spurs, substantially as shown and described.

AUGUST BUERMANN.
